UNITED STATES PATENT OFFICE.

JOHN W. BOWEN, OF JACKSONVILLE, ILLINOIS.

FOLDING SEAT OR COMMODE.

SPECIFICATION forming part of Letters Patent No. 439,797, dated November 4, 1890.

Application filed January 30, 1890. Serial No. 338,697. (No model.)

To all whom it may concern:

Be it known that I, JOHN W. BOWEN, a citizen of the United States, residing at Jacksonville, in the county of Morgan and State of Illinois, have invented certain new and useful Improvements in Folding Seats or Commodes, of which the following is a specification.

The object of my invention is to provide a cheap and simple stool or chair which can be readily folded into a compact form when not in use, and which is especially adapted for the use of infants and invalids as a commode. This object I accomplish by the use of the construction shown in the accompanying drawings; and the invention consists in certain novel features hereinafter first fully described, and then pointed out in the claims.

In the drawings referred to, Figure 1 is a central vertical section of my improved chair. Fig. 2 is a front elevation of the same. Fig. 3 is a plan view thereof. Figs. 4 and 5 are respectively a plan and edge view of the seat folded, and Fig. 6 is a detail view.

In carrying out my invention I construct the seat proper A of a series of sections or members, which are pivoted together at their ends by rule-joints, as shown at D, so that they may be folded into substantially a straight line when not in use, as shown in Fig. 4. The inner edges of the sections or members are concave, as clearly shown, so that when they are extended into their operative positions an opening is formed in the seat, as is usual in chairs of this character. It will be observed upon reference to Figs. 1 and 3 that the sections or members of the seat are arranged in two sets or series, which are joined by the hinges E, so that the sections may not only be folded into a straight line, but may be also swung toward each other, thus folding the seat upon its central transverse diameter, as indicated in dotted lines in Fig. 4.

To the outer edge of the front central section or member of the seat I secure a cross-bar I, from the front and rear sides of which curtains or aprons H J depend. These curtains hide the vessel placed beneath the seat, and the outer curtain is provided near its edge with the holes b, and is adapted to be folded over upon the seat to hide the opening therein when it is desired to use the device as a chair,

being secured in this position by engaging the holes b over the buttons a on the rear seat-sections.

The seat is supported in position for use by the standards B, to which a flexible curtain or cover C is secured. The standards extend above and below the seat, and the curtain or cover is equal in its vertical dimension to the length of the standards, so that it extends below the seat to hide the vessel placed beneath the same, and also extends above the seat to form a support for the back of the person using the device. The curtain is made of leather, canvas, or other flexible material, so that when the device is not in use the curtain can be detached and rolled around the seat to form a neat and compact bundle. The rear or central standards are provided with the lugs F on their inner sides, and the seat is supported at its rear edge by resting on said lugs. The front or end standards are provided with vertical longitudinal slots K, and these slots are engaged by the T-shaped or headed studs or lugs G at the ends of the cross-bar I to secure the said bar and standards together, and thereby support the front edge of the seat. The manner of connecting and disconnecting the bar I and the standards will be readily understood upon reference to Fig. 6. The seat and cross-bar are turned to such a position that the studs or lugs G will coincide with the slots K, after which the standards are moved toward the ends of the bar, thereby causing the slots to pass over studs when the seat is turned to a horizontal position, bringing the studs to a position at right angles to the slots and preventing their accidental disengagement.

From the foregoing description, taken in connection with the accompanying drawings, it will be seen that I have provided a very cheap and simple chair or seat, which can be readily folded into a compact bundle when not in use, and which will be firmly supported when set up for use.

The construction of my device is such that it is especially adapted for the use of infants and invalids, and its advantages are thought to be obvious.

It will be observed that in my device the curtain or cover, when the chair is in use, effectually hides the vessel beneath the same

and also furnishes an easy and comfortable rest for the back of the user. The curtains depending from the front cross-bar give the chair a somewhat ornamental appearance, and 5 the front curtain can be swung back over the seat to serve as a cushion when the device is not being used as a commode.

When the device is to be carried from one place to another, the seat is folded, as shown 10 in Figs. 4 and 5, and the curtain is then rolled around the folded seat, as will be readily understood, to serve as a cover and form a neat and compact bundle.

The device is very simple in its construction 15 and can be manufactured and sold at a small cost.

Having thus described my invention, what I claim, and desire to secure by Letters Patent, is—

20 1. A folding seat for commodes, consisting of a series of sections arranged in two sets, the sets being connected at both ends by hinges, whereby they may be swung back upon each other, and the sections of each set

being pivoted together, whereby they may be 25 turned back into a substantially straight line or turned forward so as to form a semicircle, as specified.

2. The combination of the foldable seat, the cross-bar secured to the front edge of the same 30 and having T-shaped studs at its ends, and the standards provided with slots adapted to engage said studs, as set forth.

3. The combination of the series of standards, the central or rear standards having 35 lugs on their inner sides and the front standards having longitudinal slots, the foldable seat adapted to rest upon said lugs at its rear edge, and the cross-bar secured to the front edge of the seat and provided with studs 40 at its ends adapted to engage the slots in the front standards, as set forth.

In testimony whereof I affix my signature in the presence of two witnesses.

JOHN W. BOWEN.
